Inventor
Edwin Wyckoff.

UNITED STATES PATENT OFFICE.

EDWIN WYCKOFF, OF CAMDEN, NEW JERSEY.

MARKER, FURROWER, AND COVERER.

SPECIFICATION forming part of Letters Patent No. 399,309, dated March 12, 1889.

Application filed September 7, 1888. Serial No. 284,797. (No model.)

To all whom it may concern:

Be it known that I, EDWIN WYCKOFF, a citizen of the United States, residing in the city and county of Camden, State of New Jersey, 5 have invented a new and useful Improvement in Markers, Furrowers, and Coverers, which improvement is fully set forth in the following specification and shown in the accompanying drawings.

10 My invention relates to improvements in markers, furrowers, and coverers; and it consists of a device of simple, durable, and inexpensive construction, comprising means for marking, furrowing, and covering in an efficient manner and clamping the parts.

15 Figure 1 represents a top plan view of a combined marker, furrower, and coverer embodying my invention. Fig. 2 represents a front elevation thereof, with the wheels adjusted to form a coverer. Fig. 3 represents a vertical section, the wheels being adjusted to form a furrower.

Similar letters of reference indicate corresponding parts in the several figures.

20 Referring to the drawings, A designates the frame of the device, on the axles of which are the supporting-wheels B; and C designates the draft-pole or thills thereof.

25 D designates a bow or staple secured to the frame, and one end of the rod or bar E, carrying the marker F, has an opening through which one limb of the bow or staple is passed, the staple being parallel, as shown, with the front of the frame.

30 The marker F is secured to the rod E by means of a plate, F', and yokes F'', the latter embracing the marker, which is one side of the bar E, and having their ends passing through the plate F' on the other side of the

35 bar, nuts working on the threads of the yokes clamping or binding the parts together. From this construction it is evident that the marker can be placed on either side of the machine, or can be thrown back out of the way, as shown in dotted lines in Fig. 1, and when the marker is in use the rod carrying it is adapted to fit between the uprights or lugs G on the frame, which retains said marker in place.

40 H designates a slotted bar secured to the frame, and in said slotted bar is placed the screw-threaded shanks J, having studs K,

which form axles for the furrowing and covering wheels L. Nuts J' engage the screw-threaded shanks for retaining them and the furrower and coverer in the proper adjusted 55 position. From this construction it is evident that the furrowers and coverers are laterally adjustable, and also adjustable at angles to each other to provide coverers.

50 In order that the shanks may be retained in the position to which they are adjusted in the slotted bar, a rod, M, passes through the frame and slotted bars, and is threaded to receive clamping-nuts N, which bear against the slotted bar on each side and serve to keep the 65 slot in said bar from expanding and also take up the wear on said bar.

55 The operation is as follows: When the parts are in the position shown in Fig. 2, the marker rests upon the ground, forming a guide, and 70 the wheels L are arranged in a vertical line, forming furrows as the machine moves over the ground, and when desired to use the device as a coverer the wheels are brought together and adjusted at angles to each other, 75 whereby they provide a coverer, as clearly shown in Fig. 3.

60 When the device is out of use, the furrowing and covering wheels are elevated above the ground and the marker is thrown back 80 out of the way.

65 In order to prevent the strips of the slotted bar from coming together or being broken, a block, O, is interposed in the slot, and an opening is made through said block to allow the passage of the rod M for securing the block in place.

70 It is thus evident that I provide a device which combines effectively a marker, furrower, and coverer, each serving its purpose in a thorough and perfect manner.

75 Having thus described my invention, what I claim as new, and desire to secure by Letters Patent, is—

80 1. In a marker, furrower, and coverer, a frame having lugs or uprights, a marker pivoted to the frame and retained in place by said uprights, a slotted cross-bar in the frame, threaded shanks carrying wheels or rollers adjustable vertically and angularly in said slotted bar, and a clamping-rod passing 85 through said frame and slotted bar, substantially as and for the purpose described.

2. In a marker, furrower, and coverer, a frame, a slotted bar arranged transversely in the frame, threaded shanks in said slotted bar, studs on the shanks forming axles for the covering and furrowing wheels, clamping-nuts on the threaded shanks for binding against the slotted bar for retaining said shanks in their adjusted positions, a block arranged in the slotted bar, a rod passing through the frame, 5 bar, and block, and nuts on said rod for binding against the slotted bar, all arranged and adapted to serve substantially as and for the purpose described.

3. In a marker, furrower, and coverer, a frame, a transverse slotted bar carried thereby, shanks carrying wheels adjustable vertically and angularly in said slotted bar, nuts on said shanks for retaining the same in the adjusted positions, and a rod passing through the frame, and slotted bars having clamping-nuts thereon, all arranged and adapted to serve substantially as and for the purpose set forth.

EDWIN WYCKOFF.
